UNITED STATES PATENT OFFICE.

CHARLES W. HARROLD, OF WARREN, OHIO, ASSIGNOR TO THE HARRIS AUTOMATIC PRESS COMPANY, OF NILES, OHIO, A CORPORATION OF OHIO.

SHEET-FEEDER.

1,275,679.

Specification of Letters Patent. Patented Aug. 13, 1918.

Application filed February 28, 1916. Serial No. 80,937.

To all whom it may concern:

Be it known that I, CHARLES W. HARROLD, a citizen of the United States, and a resident of Warren, in the county of Trumbull 5 and State of Ohio, have invented certain new and useful Improvements in Sheet-Feeders, of which the following is a specification.

My invention relates to mechanism for 10 successively separating and feeding sheets of paper or similar material, and relates more particularly to machines for automatically feeding paper bags or sacks, when flattened out and stacked in a pile, to a printing-press 15 or like machine, such feeders being mechanically operated and having the feeding mechanism include a suction separator combined with other novel instrumentalities to produce the requisite action in separating 20 and feeding forward the successive sheets or bags from the pile.

The objects of my invention are, among other things, to provide mechanism whereby the individual sheets or bags may be detached and fed from the stack or pile rapidly, and without any break or intermission in the forward succession of sheets, and furthermore, without disturbing or disarranging the balance of the pile; also to provide 25 means for intermittently releasing the pressure or weight of the pile upon the sheet which is being separated and withdrawn, while holding the balance of the pile firmly in place. A further object is to provide a 30 feeder of this general character of simple and efficient construction and operation, with parts that are durable and not apt to get out of order.

The invention will be hereinafter fully 35 set forth and explained, and particularly pointed out in the claims.

The accompanying drawings show one embodiment of my invention, and serve, in connection with the description herein, to 40 fully explain the principles of my invention, and the best mode in which I have contemplated applying those principles in practice.

Figure 1 is a side elevation of my improved feeding apparatus;

Fig. 2 is an end view thereof looking from the left in Fig. 1;

Fig. 3 is an enlarged sectional plan view, the section being taken on the line 3—3 55 shown in Fig. 1;

Fig. 4 is a diagrammatic view illustrating one of the suckers engaging the upper portion of the pile and about to detach the outermost sheet;

Fig. 5 is a fragmentary diagrammatic view illustrating one of the suckers carrying the outermost sheet from the pile;

Fig. 6 is a diagrammatic view illustrating the upper pull-out roll lowered to withdraw the sheet or bag from the pile;

Fig. 7 is an enlarged sectional fragmentary view of the sucker shaft, and one of the suckers mounted thereon;

Fig. 8 is a sectional view on the line 8—8 shown in Fig. 7;

Fig. 9 is an enlarged side view of a form of vacuum controlling valve for the suckers; and

Fig. 10 is an end view of the controlling valve shown in Fig. 9.

Similar numerals refer to similar parts throughout the several figures.

Referring to the drawings, 11 indicates the end parts or standards of the frame of my sheet-feeder, composed of any suitable 80 material, and formed in any desired shape to accommodate the various structural parts comprising the feeder. These standards 11 may be properly connected by cross-bars or other ties, to provide a sufficiently strong 85 and rigid structure. A main driving shaft 12 is suitably journaled in the standards 11, and secured thereto is a driving pulley (not shown) for receiving power to drive the 90 feeder. Secured to the shaft 12 is the driving gear 13 enmeshed with the gear 14 mounted on the cam-shaft 15, to which are secured the various cam mechanisms and other devices for operating the different 95 members comprised in my feeder, all of which will be hereafter described. Mounted on the cam-shaft 15 is the large gear 16, which engages with the gear 17 secured to the shaft 18, to which are affixed the lower 100 pull-out rolls 19. The gear 16 also engages with the idler gear 20, journaled on the stud 21 secured to the frame 11, and this gear 20 also engages with the gear 22 mounted on the transverse shaft 23. This shaft 23 carries the rock-levers 24 (only one being 105 shown), the inner arms 25 of which levers 24 have journaled in their ends the shaft 26, to which are secured the upper pull-out rolls 27 (preferably three in number, as shown in Fig. 2). Mounted on the shaft 26 110

is the gear 28 which engages the idler gear 29 pivoted on the stud 30 secured to the rock-lever 24, which gear 29 enmeshes with the gear 22 on the shaft 23. I prefer to 5 construct the pull-out rolls 19 and 27, as shown in Figs. 2 and 3; each set of these pull-out rolls 19 and 27 are preferably three in number, and are constructed in the form 10 of circular disks each mounted on their respective shafts 18 and 26, so as to coöperate with one another in pairs when in contact, as shown in Fig. 2, and are also disposed to have suitable spaces between the separate pairs to 15 accommodate the hereinafter described suc- 15 tion devices. The respective lower and upper rolls 19 and 27 are adapted to rotate in unison and at the same peripheral speeds, through the chain of gearing which I have just described, the rolls revolving in the di- 20 rection of the arrows shown in Fig. 6; and the size of the respective gears 14 and 16 is such that the pull-out roller shafts 18 and 26 will make substantially two and three revolutions respectively, while the shaft 15 25 makes a single revolution, as will be readily understood by those skilled in the art.

Mounted on the opposite end of the driving-shaft 12 (Fig. 2) is the disk 31 which carries the pin 32 upon which is pivoted the 30 piston rod 33 projecting from the cylinder 34 affixed to the bracket 35 on the lower part of the frame 11, as shown in Fig. 2. The cylinder 34, with the piston therein, may be of any suitable construction to pro- 35 duce a vacuum of sufficient degree to operate the separating suckers, which will be hereinafter described.

Referring to Figs. 4, 5 and 6, 36 indicates the stack or pile of superimposed sheets or 40 bags of paper or other material which are to be separated one by one and withdrawn and fed forward from my feeder. Preferably the pile of sheets 36 is arranged and disposed with their contiguous edges in aline- 45 ment, and resting on edge in a slightly inclined position in a suitable rack or hopper formed in the frame 11, as shown in Figs. 4 and 6. However, it will be understood that my feeder will operate equally as well 50 when the pile 36 is arranged vertically or at any intermediate angle; the inclination which I have shown in Fig. 4 has been found in practice very desirable in separating and feeding the sheets. As shown in these fig- 55 ures, the lower edges of the pile 36 rest upon a series of right-angled pile supports 37 having the upper parts carrying the brackets 38 mounted on the transverse shaft 39; these supports are adjustable on the shaft 39 to 60 secure the proper angle of inclination through the set-screws 40, shown in Fig. 6. Disposed against the central lower portion of the pile 36 is a pair of pile release fingers 41 mounted on the rock-shaft 42, the 65 fingers 41 having a reciprocating forward

and backward movement on the shaft 42, since I prefer to hold the lower portion of the pile 36 in a slightly curved or convexly buckled position by the fingers 41 being normally held slightly advanced from the transverse plane of the pile supports 37; the fingers 41 are shown in their normally advanced position by dotted lines in Fig. 4 (only one being shown). The reciprocating movement of the fingers 41 is accomplished by the following mechanism: Mounted on the shaft 42 is the arm 43, having pivoted to its end the link 44 carrying the cam-roller 45 adapted to engage the cam 46 mounted on the cam-shaft 15. The outer end of the link 44 is slotted at 47, as shown in Figs. 4 and 6, through which slot 47 the shaft 15 passes as the link 44 is horizontally reciprocated through its engagement with the revolving cam 46. The coil spring 48 connects the arm 43 with the cross rod 49, and tends to pull the fingers 41 away from the pile when they are not held in their advanced position by the roller 45 riding along the high part of the cam 46. It will be understood the retraction of the fingers 41 is timed in conjunction with the withdrawal of the lower portion of the outermost sheet from the pile 36, as the front edge is seized by the pull-out rolls, as shown in Fig. 6, 90 so that this separated sheet may be readily removed from the pile without tearing and with less friction than if the dead weight of the pile bore against this sheet which is being withdrawn and fed forwardly from the pile 36. The retraction of the fingers 41 is so abrupt and rapid that the inertia of the pile itself prevents the inherent weight of the associated sheets constituting the balance of the pile from immediately or closely following 100 the retracted support-fingers 41; it is during this instant of relieved pressure or inherent weight, that the outermost sheet theretofore seized by the suckers (hereinafter described) begins to withdraw from the pile 36. The inherent weight of the pile on the support-fingers 41 may have returned to normal before the sheet is fully withdrawn, yet the quick retraction of these supports has served its purpose in relieving the inherent weight 110 of the pile itself at the very instant of the starting of the outermost sheet so that this detached sheet is under headway, and its bearing surface with attending friction is constantly and rapidly being reduced in 120 area as the sheet is withdrawn from the pile.

The upper portion of the pile 36 is held in position by a series of hold-back fingers 50 secured in brackets 51 mounted on the rock-shaft 52, journaled in the frame 11. 125 Secured to the rock-shaft 52 is the rock-arm 53 having pivoted on its end the link 54 carrying the cam-roller 55 adapted to be engaged by the cam 56 mounted on the cam-shaft 15. The outer end of the link 54 is 130

slotted at 57 through which slot the cam-shaft 15 passes, as the link 54 is reciprocated, as shown in Figs. 4 and 6, to lift and lower the hold-back fingers 50 from the upper edges of the pile 36. The coil spring 58, connecting the pin 59 on the link 54 to the cross-rod 60, normally holds the roller 55 in contact with the cam 56. The movement of the fingers 50 is timed through the form and 10 mounting of the cam 56, so that the fingers will be lifted just as the sheet-detaching means are raised to engage the outermost sheet from the pile 36, as shown in Fig. 4, and the fingers 50 return to their lowered 15 position, as shown in Fig. 5, as soon as the upper edge of the detached sheet has been lowered sufficiently to carry the upper edge of the sheet out of the range of the descent of the fingers 50. Preferably, I also provide 20 a series of inclined flexible spring fingers 61, affixed to the cross-rod 62, which fingers 61 bear down upon the upper edges of the pile 36, as shown in Fig. 6; also mounted on the rod 62 are the depending 25 brackets 63, having secured, at right angles to their ends, the flexible spring clips 64, which are arranged to extend outside the pile 36, and project laterally slightly within the side edges of the pile, as shown in Fig. 30 2, so as to contact with the outermost sheet of the pile 36 along the side margins of the sheets, giving an added rigidity to the upper part of the pile 36 in its supporting 35 rack or hopper.

35 The sheet-detaching means comprises a series of suckers 65 (in this case four in number) mounted at the same transverse plane on the tubular shaft 66, and disposed on the shaft 66 so as to be reciprocated in 40 the spaces between the pull-out rolls, as shown in Figs. 2 and 3. The construction of these suckers is shown more particularly in Figs. 7 and 8, and consists of the hollow L-shaped arm 67 mounted at right angles to 45 the tubular shaft 66 with its hollow bore 68 engaging the port 69 in the shaft 66, as shown in Fig. 7; the outer end of the arm 67 is screw-threaded at 70, and secured thereto is the block 71 carrying the flaring, 50 conically-shaped lips 72, composed of rubber or other suitably yielding material, to engage the surface of the outermost sheet. Secured to one end of the tubular shaft 66 is the pipe 73, which leads to the sucker control valve mechanism shown in detail in 55 Figs. 9 and 10. Any suitable form of valve mechanism may be used to regulate the proper action of the suckers by making and breaking the vacuum therein. The device I have shown is constructed as follows: 60 Mounted on the frame 11 is the cylindrical valve box 74 connected to the tubular shaft 66 by the flexible pipe 73 through the port 75; the pipe 76 connects the box 74 through 65 the port 77 with the vacuum cylinder 34, as shown in Fig. 2. Journaled upon the box 74 is the oscillating valve 78 having cut in its inner surface the segmental opening 79 arranged to connect, in one position, the ports 75 and 77, as shown in Fig. 9, thereby creating a vacuum within the rubber lips 72, and in another position, as shown in Fig. 10, to connect the port 75 with the vent 80, which causes the suckers 65 to release their hold on the detached sheet. The oscillating movement of the valve 78 is secured and controlled by the cam 81 mounted on the cam-shaft 15, the cam 81 engaging with the cam-roller 82 pivoted to the arm 83 secured to the valve 78, as shown in Figs. 3, 9 and 10. When the arm 83 is moved to the left, as shown in Fig. 9, the suckers 65 are in direct communication with the vacuum cylinder 34, through the tubular shaft 66, pipe 73, port 75, opening 79, port 77, and pipe 76. Fig. 10 shows the opening 79 connecting the port 75 and vent 80.

The suckers 65 are preferably mounted upon the shaft 66 with arms 67 of sufficient length and shape that they will engage the outermost sheet of the pile 36 along the upper margin thereof, the two exterior suckers contacting with this outer sheet near the upper corners thereof, as shown in Figs. 2 and 4. The tubular shaft 66, carrying, and serving as a common axis for, the suckers 65, extends transversely across the feeder, and is pivotally mounted at the ends in the journal bearings 84 and 85 carried by the rock-levers 86 and 87, pivoted on either side of the frame 11 on the studs 88 and 89 respectively, as shown in Fig. 2. The opposite arms 90 and 91 of the rock-levers 86 and 87 respectively are connected by the links 92 and 93, to the crank-arms 94 and 95 respectively mounted in suitable relation to each other on opposite ends of the cam-shaft 15, as shown in Fig. 3. To secure an oscillatory motion, or partial rotation for the shaft 66 on its axis, I have rigidly secured thereto the arm 97 connected by the link 98 pivoted to a stud 99 in the frame 11, as shown in Figs. 3 and 6. Through the rocking of the levers 86 and 87 by the mechanism just described, the shaft 66 rises and falls through the segmental slot 100 formed in the frame 11, and in so doing the shaft 66 is partially rotated in a clockwise direction when moving upwardly, the arm 97 being drawn to the right (Fig. 4), and in a contra-clockwise direction when the shaft 66 is lowered through the slot 100, by the arm 97 and its connecting link 98 swinging to the left, as shown in Fig. 6. The swinging upward and downward movement of the shaft 66 in the slot 100, combined with its complementary oscillatory or rotating action, causes the suckers 65 to be successively lifted and lowered so as to successively engage, detach, and bend down the upper portion of the outermost sheet 101.

to be seized by the pull-out rolls 19 and 27, to be thereafter withdrawn from the pile and fed forwardly to the feed-table 102 (Fig. 6). A pair of guide wheels 103 are loosely mounted on the shaft 66, and when this shaft is in its highest position, as shown in Fig. 4, the peripheries of these guide wheels 103 bear against the outermost sheet 101 of the pile 36, and the sheet is carried over such wheels while being withdrawn from the pile, as shown in Fig. 6.

The rotating upper pull-out rolls 27 are constructed so as to have a raising and lowering movement in relation with the rotating lower pull-out rolls 19, the shaft 26, upon which the rolls 27 are mounted, rising and falling through the slot 104 formed in the upper part of the frame 11. The rolls 27 are raised to form an opening in conjunction with their respective rolls 19 toward and into which the suckers 65 first detach and then bend down the outermost sheet 101 from the pile 36; then the rolls 27 descend and contact with the lower rolls to seize this separated sheet slightly to the rear of the front edge, as shown in Fig. 6, then the rotating rolls 19 and 27 carry away the sheet to the feed-table 102. The means provided to raise and lower the upper rolls 27 comprises the following: Mounted on the shaft 23 which carries the rock-levers 24 supporting the upper roll carrying shaft 26, is the rock-arm 105, the end of which carries the link 106, slotted at 107, within which slot the cam-shaft 15 passes as the link 106 is reciprocated; the outer end of the link 106 carries the cam-roller 108 adapted to engage the cam 109 mounted on the shaft 15. When the cam-roller 108 rides along the high part of the cam 109, as shown in Fig. 4, the upper rolls 27 are lifted; when the roller 108 contacts with the drop of the cam 109, as shown in Fig. 6, the upper rolls 27 are in contact with their respective lower rolls 19, and the front margin of the outermost sheet 101 is caught therebetween, ready to be withdrawn from the pile 36, the suckers 65 having released their hold and passed below the line of opening between the two sets of pull-out rolls.

The operation of my sheet feeder is substantially as follows: The stack or pile 36 of sheets, bags or blanks to be separated and fed is placed within the rack or hopper 55 formed as has been already shown and described with the pile release fingers 41 in their advanced position, causing the pile to slightly buckle along the central lower portion. The respective cams 46, 56, 81 and 60 109, having substantially the forms shown in the figures, are severally mounted and secured to the cam-shaft 15 in suitable relation with the position of the crank-arms 94 and 95, and with one another, as to first cause the suckers 65 to be lifted and par-

tially rotated to contact with, and engage, the outermost sheet 101 of the pile, as shown in Fig. 4, the hold-back fingers 50 having been meanwhile lifted as soon as the series of suckers contact with the pile. The suckers 65 engage the upper margin of the sheet 101 as well as the extreme corners, and the suction control valve 78 has been opened, just prior to the contact of the suckers with the outermost sheet, by the cam 81, thereby connecting all the suckers with the vacuum cylinder 84, the parts constituting the valve mechanism being in the position shown in Fig. 9. The simultaneous action of all four suckers in fastening themselves to the upper margin of the sheet 101 tends to loosen same and to admit air between such sheet 101 and the second sheet, which aids in detaching and separating the sheet 101 from the pile without tearing, and also without disarranging the remainder of the pile. As soon as the suckers 65 have fastened themselves to the outermost sheet 101, they are quickly swung away from the plane of the pile 36 and lowered from their raised position while the shaft 66 is partially rotated counter-clockwise during this movement, and the suckers snap the lateral edges of the sheet 101 by the clips 64, which immediately thereafter engage and hold the remainder of the pile 36 in its rigid position. Meanwhile the hold-back fingers 50 have been lowered to hold the front upper edges of the pile 36, as shown in Fig. 5. The sheet 101, its upper portion being now detached from the pile, is then bent over the guide wheels 103, as shown in Fig. 5, through the lowering movement of the suckers 65. As soon as the upper edge of the sheet or bag 101 has been carried below the peripheries of the uplifted upper pull-out rolls 27, the cam-roller 108 rides off the high part of the upper roll cam 109, which rocks the lever 24 to lower the upper rolls 27 to close the opening between the rolls 27 and the rolls 19 to seize the front margin of the sheet 101. The rolls 27, in dotted lines in Fig. 5, are shown partially lowered, ready to engage the front margin of the sheet, while the suckers 65 have descended and bent this sheet 101 so that it is nearly in contact with the peripheries of the rolls 19. As soon as the rolls 27 have been completely lowered, as shown in Fig. 6, the front margin of the sheet is caught in the bite of the peripheries of the rolls 19 and 27, and simultaneously therewith the valve 78 is moved to connect the suckers with the atmosphere, through the vent 80, whereby the suckers release their hold on the sheet, and, at the same time, the cam-roller 46 rides off the high part of the cam 46, enabling the spring 48 to swing the arm 48 to the left (Fig. 6) which retracts the pile release fingers 41, thereby momentarily straightening the pile 36 from its nor-

mal buckled position. This combined simultaneous action enables the outermost sheet 101 to be free from the suckers and from the dead weight or pressure of the pile, and to 5 be rapidly and readily withdrawn therefrom by the pull-out rolls 19 and 27 over the guide wheels 103, and deposited on the feed-table 102, all as shown in Fig. 6. The suckers 65, it will be noted, have been lowered below 10 and beyond the range of the path of the sheet 101 over the guide wheels 103, and through the opening between the two sets of pull-out rolls, which have a high peripheral speed, as hereinbefore set forth, and their 15 peripheral length through their faster revolutions, for each cycle of operations, is amply sufficient to deliver the sheet from the pile and carry same forwardly to the feed-table 102. Thereafter the fingers 41 are again advanced to buckle the pile, and the suckers 65 are about to rise in the next cycle of operations to remove the second sheet from the pile.

I claim as my invention:

- 25 1. In a sheet-feeder, the combination with a support for a pile of sheets on edge, comprising a series of vertically movable hold-back fingers engaging the upper margins of the pile, of a pair of flexible clips bearing 30 against the side margins of the pile, means for detaching the outermost sheet from the clips, when the fingers are raised, and withdrawing same from the pile, and means for lowering said fingers when said sheet is detached from the pile.
2. In a sheet-feeder, the combination with an inclined support for a pile of sheets on edge, comprising a series of vertically movable hold-back fingers engaging the upper 40 margins of the pile, of a pair of flexible clips bearing against the side margins of the pile, and means for detaching the outermost sheet from the clips, when the fingers are raised, and withdrawing same from the pile, and means for lowering said fingers when 45 said sheet is detached from the pile.
3. In a sheet-feeder, the combination with a support for a pile of sheets on edge, comprising a series of vertically movable hold-back fingers engaging the upper margins of the pile, of a pair of flexible clips bearing 50 against the side margins of the pile, means for detaching the outermost sheet from the clips, when the fingers are raised, and withdrawing same from the pile, and means for 55 relieving the inherent weight of the pile upon the detached sheet during its withdrawal from the pile.
4. In a sheet-feeder, the combination with 60 an inclined support for a pile of sheets on edge, comprising a series of vertically movable hold-back fingers engaging the upper margins of the pile, of a pair of flexible clips bearing against the side margins of the pile, 65 means for detaching the outermost sheet

from the clips, when the fingers are raised, and withdrawing same from the pile, and means for relieving the inherent weight of the pile upon the detached sheet during its withdrawal from the pile.

5. In a sheet-feeder, the combination with a support for a pile of sheets on edge, comprising a series of vertically movable hold-back fingers engaging the upper margins of the pile, of a pair of flexible clips bearing 70 against the side margins of the pile, means for detaching the outermost sheet from the clips, when the fingers are raised, and withdrawing same from the pile, and means for simultaneously relieving the inherent weight 75 of the pile upon the detached sheet during its withdrawal from the pile.

6. In a sheet-feeder, the combination with an inclined support for a pile of sheets on edge, comprising a series of vertically movable hold-back fingers engaging the upper margins of the pile, of a pair of flexible clips bearing 80 against the side margins of the clips, when the fingers are raised, and withdrawing same from the pile, and means for simultaneously relieving the inherent weight 85 of the pile upon the detached sheet during its withdrawal from the pile.

7. In a sheet-feeder, the combination with a support for a pile of sheets on edge, comprising a series of vertically movable hold-back fingers engaging the upper margins of the pile, of a pair of flexible clips bearing 90 against the side margins of the pile, means for detaching the outermost sheet from the 95 clips, when the fingers are raised, and withdrawing same from the pile, and means for simultaneously and momentarily relieving the inherent weight of the pile upon the detached sheet during its withdrawal from the 100 pile.

8. In a sheet-feeder, the combination with an inclined support for a pile of sheets on edge, comprising a series of vertically movable hold-back fingers engaging the upper 110 margins of the pile, of a pair of flexible clips bearing against the side margins of the pile, means for detaching the outermost sheet from the clips, when the fingers are raised, and withdrawing same from the pile, 115 and means for simultaneously and momentarily relieving the inherent weight of the pile upon the detached sheet during its withdrawal from the pile.

9. In a sheet feeder, the combination with 120 a support for a pile of sheets, of pneumatic suction devices rotatably mounted to detach the upper end of the outer sheet from the pile, coacting reciprocable means for engaging said detached upper end and drawing 125 the sheet from the pile, and rotatable means carried by the suction devices over which said detached end is bent within said sheet-engaging means.

10. In a sheet feeder, the combination 130

- with a support for a pile of sheets, of pneumatic suction devices rotatably mounted to detach the upper end of the outer sheet from the pile, coacting vertically reciprocatable means for engaging said detached upper end and drawing the sheet from the pile, and rotatable means carried by the suction devices over which said detached end is bent within said sheet-engaging means.
- 10 11. In a sheet feeder, the combination with a support for a pile of sheets, of pneumatic suction devices rotatably mounted to detach the upper end of the outer sheet from the pile, coacting reciprocatable rollers positively driven at a like peripheral speed for engaging said detached upper end and drawing the sheet from the pile, and rotatable means carried by the suction devices over which said detached end is bent within said sheet-engaging means.
- 15 12. In a sheet feeder, the combination with a support for a pile of sheets, of pneumatic suction devices rotatably mounted to detach the upper end of the outer sheet from the pile, coacting vertically reciprocatable rollers positively driven at a like peripheral speed for engaging said detached upper end and drawing the sheet from the pile, and rotatable means carried by the suction devices over which said detached end is bent within said sheet-engaging means.
- 20 13. In a sheet-feeder, the combination with a support for a pile of sheets, of means for detaching one end of the outer sheet from the pile, separate reciprocatable means for engaging said detached end and drawing the sheet from the pile, and means for relieving the inherent weight of the pile upon the detached sheet during its withdrawal from the pile.
- 25 14. In a sheet-feeder, the combination with a support for a pile of sheets, of means for detaching one end of the outer sheet from the pile, separate vertically reciprocatable means for engaging said detached end and drawing the sheet from the pile, and means for relieving the inherent weight of the pile upon the detached sheet during its withdrawal from the pile.
- 30 15. In a sheet-feeder, the combination with a support for a pile of sheets, of means for detaching one end of the outer sheet from the pile, separate vertically reciprocatable rotary means for engaging said detached end and drawing the sheet from the pile, and means for relieving the inherent weight of the pile upon the detached sheet during its withdrawal from the pile.
- 35 16. In a sheet-feeder, the combination with a support for a pile of sheets, of means for detaching one end of the outer sheet from the pile, separate vertically reciprocatable means for engaging said detached end and drawing the sheet from the pile, and means for relieving the inherent weight of the pile upon the detached sheet during its withdrawal from the pile.
- 40 17. In a sheet-feeder, the combination with a support for a pile of sheets, of means for detaching one end of the outer sheet from the pile, separate vertically reciprocatable rotary means for engaging said detached end and drawing the sheet from the pile, and means for momentarily relieving the inherent weight of the pile upon the detached sheet during its withdrawal from the pile.
- 45 18. In a sheet-feeder, the combination with a support for a pile of sheets, of means for detaching one end of the outer sheet from the pile, separate vertically reciprocatable rotary means for engaging said detached end and drawing the sheet from the pile, and means for momentarily relieving the inherent weight of the pile upon the detached sheet during its withdrawal from the pile.
- 50 19. In a sheet-feeder, the combination with a support for a pile of sheets, of means for detaching one end of the outer sheet from the pile, separate reciprocatable means for engaging said detached end and drawing the sheet from the pile, and means for simultaneously and momentarily relieving the inherent weight of the pile upon the detached sheet during its withdrawal from the pile.
- 55 20. In a sheet-feeder, the combination with a support for a pile of sheets, of means for detaching one end of the outer sheet from the pile, separate vertically reciprocatable means for engaging said detached end and drawing the sheet from the pile, and means for simultaneously and momentarily relieving the inherent weight of the pile upon the detached sheet during its withdrawal from the pile.
- 60 21. In a sheet-feeder, the combination with a support for a pile of sheets, of means for detaching one end of the outer sheet from the pile, separate vertically reciprocatable rotary means for engaging said detached end and drawing the sheet from the pile, and means for simultaneously and momentarily relieving the inherent weight of the pile upon the detached sheet during its withdrawal from the pile.
- 65 22. In a sheet-feeder, the combination with a support for a pile of sheets, of means for detaching one end of the outer sheet from the pile, means carried by said detaching means to support the body of the pile while said detaching means are in action, reciprocatable cooperating pull-out rolls for engaging said detached end, means for rotating the rolls to withdraw the detached sheet from the pile, and means for relieving the inherent weight of the pile upon the detached sheet.
- 70 23. In a sheet-feeder, the combination

- with a support for a pile of sheets, of means for detaching one end of the outer sheet from the pile, means carried by said detaching means to support the body of the pile while said detaching means are in action, vertically reciprocatable coöperating pull-out rolls for engaging said detached end, means for rotating the rolls to withdraw the detached sheet from the pile, and means for relieving the inherent weight of the pile upon the detached sheet.
24. In a sheet-feeder, the combination with a support for a pile of sheets, of means for detaching one end of the outer sheet from the pile, means carried by said detaching means to support the body of the pile while said detaching means are in action, of reciprocatable coöperating pull-out rolls for engaging said detached end, means for rotating the rolls to withdraw the detached sheet from the pile, and means for simultaneously relieving the inherent weight of the pile upon the detached sheet.
25. In a sheet-feeder, the combination with a support for a pile of sheets, of means for detaching one end of the outer sheet from the pile, means carried by said detaching means to support the body of the pile while said detaching means are in action, vertically reciprocatable coöperating pull-out rolls for engaging said detached end, means for rotating the rolls to withdraw the detached sheet from the pile, and means for simultaneously relieving the inherent weight of the pile under the detached sheet.
26. In a sheet-feeder, the combination with a support for a pile of sheets, of means for detaching one end of the outer sheet from the pile, means carried by said detaching means to support the body of the pile while said detaching means are in action, reciprocatable coöperating pull-out rolls for engaging said detached end, means for rotating the rolls to withdraw the detached sheet from the pile, and means for momentarily relieving the inherent weight of the pile upon the detached sheet.
27. In a sheet-feeder, the combination with a support for a pile of sheets, of means for detaching one end of the outer sheet from the pile, means carried by said detaching means to support the body of the pile while said detaching means are in action, vertically reciprocatable coöperating pull-out rolls for engaging said detached end, means for rotating the rolls to withdraw the detached sheet from the pile, and means for momentarily relieving the inherent weight of the pile upon the detached sheet.
28. In a sheet-feeder, the combination with a support for a pile of sheets, of means for detaching one end of the outer sheet from the pile, means carried by said detaching means to support the body of the pile while said detaching means are in action, reciprocatable coöperating pull-out rolls for engaging said detached end, means for rotating the rolls to withdraw the detached sheet from the pile, and means for simultaneously and momentarily relieving the inherent weight of the pile upon the detached sheet.
29. In a sheet-feeder, the combination with a support for a pile of sheets, of means for detaching one end of the outer sheet from the pile, means carried by said detaching means to support the body of the pile while said detaching means are in action, vertically reciprocatable coöperating pull-out rolls for engaging said detached end, means for rotating the rolls to withdraw the detached sheet from the pile, and means for simultaneously and momentarily relieving the inherent weight of the pile upon the detached sheet.
30. In a sheet-feeder, the combination with an inclined support for a pile of sheets on edge, of means comprising a pneumatic sucker for detaching one end of the outer sheet from the pile, means for moving said sucker toward and from the pile, means for oscillating said sucker in unison with said sucker-moving means, means carried by said sucker to support the body of the pile while said sucker is in action, an air-exhausting means to produce a partial vacuum in the sucker, means for breaking said vacuum, two coacting reciprocatable rotary means having the same peripheral speed for directly engaging said detached end and drawing the sheet from the pile, and means for operating said vacuum-breaking means when said rotary means has engaged the detached sheet.
31. In a sheet-feeder, the combination with a support for a pile of sheets, of means comprising a pneumatic sucker for detaching one end of the outer sheet from the pile, means for moving said sucker toward and from the pile, means comprising a rock-arm and link connection with the feeder, for simultaneously oscillating said sucker in unison with said sucker-moving means, means carried by said sucker to support the body of the pile while said sucker is in action, an air-exhausting means to produce a partial vacuum in the sucker, means for breaking said vacuum, reciprocatable rotary means for engaging said detached end and drawing the sheet from the pile, and means for operating said vacuum-breaking means when said rotary means has engaged the detached sheet.
32. In a sheet-feeder, the combination with a support for a pile of sheets, of means comprising a pneumatic sucker for detaching one end of the outer sheet from the pile, means for moving said sucker toward and

- from the pile, means comprising a rock-arm and link connection with the feeder, for oscillating said sucker in unison with said sucker-moving means, means carried by said sucker to support the body of the pile while said sucker is in action, an air-exhausting means to produce a partial vacuum in the sucker, means for breaking said vacuum, vertically reciprocatable rotary means for 5 engaging said detached end and drawing the sheet from the pile, and means for operating said vacuum-breaking means when said rotary means has engaged the detached sheet.
- 15 33. In a sheet-feeder, the combination with a support for a pile of sheets, of means comprising a pneumatic sucker for detaching one end of the outer sheet from the pile, means for moving said sucker toward and 20 from the pile, means comprising a rock-arm and link connection with the feeder, for simultaneously oscillating said sucker in unison with said sucker-moving means, means carried by said sucker to support the 25 body of the pile while said sucker is in action, an air-exhausting means to produce a partial vacuum in the sucker, means for breaking said vacuum, vertically reciprocatable rotary means for engaging said detached end and drawing the sheet from the pile, and means for operating said vacuum-breaking means when said rotary means has 30 engaged the detached sheet.
34. In a sheet-feeder, the combination 35 with a support for a pile of sheets, of means comprising a pneumatic sucker for detaching one end of the outer sheet from the pile, means for moving said sucker toward and from the pile, means for oscillating said 40 sucker in unison with said sucker-moving means, an air-exhausting means to produce a partial vacuum in the sucker, means for breaking said vacuum, reciprocatable rotary means for engaging said detached end and 45 drawing the sheet from the pile, means for operating said vacuum-breaking means when said rotary means has engaged the detached sheet, and means for relieving the inherent weight of the pile upon said sheet 50 during withdrawal.
35. In a sheet-feeder, the combination with a support for a pile of sheets, of means comprising a pneumatic sucker for detaching one end of the outer sheet from the pile, means for moving said sucker toward and from the pile, means for simultaneously 55 oscillating said sucker in unison with said sucker-moving means, an air-exhausting means to produce a partial vacuum in the 60 sucker, means for breaking said vacuum, reciprocatable rotary means for engaging said detached end and drawing the sheet from the pile, means for operating said vacuum-breaking means when said rotary
- means has engaged the detached sheet, and means for relieving the inherent weight of the pile upon said sheet during withdrawal.
36. In a sheet-feeder, the combination with a support for a pile of sheets, of means comprising a pneumatic sucker for detaching one end of the outer sheet from the pile, means for moving said sucker toward and from the pile, means for oscillating said sucker in unison with said sucker-moving means, an air-exhausting means to produce a partial vacuum in the sucker, means for breaking said vacuum, vertically reciprocatable rotary means for engaging said detached end and drawing the sheet from the pile, means for operating said vacuum-breaking means when said rotary means has engaged the detached sheet, and means for relieving the inherent weight of the pile upon said sheet during withdrawal.
37. In a sheet-feeder, the combination with a support for a pile of sheets, of means comprising a pneumatic sucker for detaching one end of the outer sheet from the pile, means for moving said sucker toward and from the pile, means for simultaneously oscillating said sucker in unison with said sucker-moving means, an air-exhausting means to produce a partial vacuum in the sucker, means for breaking said vacuum, vertically reciprocatable rotary means for engaging said detached end and drawing the sheet from the pile, means for operating said vacuum-breaking means when said rotary means has engaged the detached sheet, and means for relieving the inherent weight of the pile upon said sheet during withdrawal.
38. In a sheet-feeder, the combination with a support for a pile of sheets, of a pair of rotatable pull-out rolls, means to separate said rolls to make an opening therebetween, means to detach one end of the outer sheet from the pile, rotatable means carried by said detaching means over which the sheet is bent into said opening, means to draw said rolls together to engage said detached end, coacting oscillating means to operate all said means in proper succession, and means for rotating said rolls in unison to draw the sheet from the pile.
39. In a sheet-feeder, the combination with a support for a pile of sheets, of a pair of rotatable pull-out rolls, means to move one of said rolls to make an opening therebetween, means to detach one end of the outer sheet from the pile, rotatable means carried by said detaching means over which the sheet is bent into said opening, means to move said separated roll into contact with the other roll to engage said detached end, coacting oscillating means to operate all said means in proper succession, and means for rotating said rolls in unison to draw the sheet from the pile.

40. In a sheet-feeder, the combination with a support for a pile of sheets, of a pair of rotatable pull-out rolls, means to separate said rolls to make an opening therebetween, means to detach one end of the outer sheet from the pile and bend same into said opening, means to draw said rolls together to engage said detached end, means for rotating said rolls in unison to draw the sheet from the pile, and means for relieving the inherent weight of the pile upon said sheet during withdrawal.

41. In a sheet-feeder, the combination with a support for a pile of sheets, of a pair of rotatable pull-out rolls, means to move one of said rolls to make an opening therebetween, means to detach one end of the outer sheet from the pile and bend same into said opening, means to move said separated roll into contact with the other roll to engage said detached end, means for rotating said rolls in unison to draw the sheet from the pile, and means for relieving the inherent weight of the pile upon said sheet during withdrawal.

42. In a sheet-feeder, the combination with a support for a pile of sheets, of a pair of rotatable pull-out rolls, means to separate said rolls to make an opening therebetween, means to detach one end of the outer sheet from the pile and bend same into said opening, means to draw said rolls together to engage said detached end, means for rotating said rolls in unison to draw the sheet from the pile, and means for momentarily relieving the inherent weight of the pile upon said sheet during withdrawal.

43. In a sheet-feeder, the combination with a support for a pile of sheets, of a pair of rotatable pull-out rolls, means to move one of said rolls to make an opening therebetween, means to detach one end of the outer sheet from the pile and bend same into said opening, means to move said separated roll into contact with the other roll to engage said detached end, means for rotating said rolls in unison to draw the sheet from the pile, and means for momentarily relieving the inherent weight of the pile upon said sheet during withdrawal.

44. In a sheet-feeder, the combination with a support for a pile of sheets, of a pair of rotatable pull-out rolls, means to move one of said rolls to make an opening therebetween, a pneumatic sucker for detaching one end of the outer sheet from the pile, means for moving said sucker toward and from the pile, means for oscillating said sucker in coöperative relation with said sucker-moving means, an air-exhausting means to produce a partial vacuum in the sucker, means for breaking said vacuum, means to move said separated roll into contact with the other roll to engage said de-

tached end, means for operating said vacuum-breaking means when said rolls have engaged said sheet, and means for rotating said rolls in unison to draw the sheet from the pile.

45. In a sheet-feeder, the combination with a support for a pile of sheets, of a pair of rotatable pull-out rolls, means to move one of said rolls to make an opening therebetween, a pneumatic sucker for detaching one end of the outer sheet from the pile, means for moving said sucker toward and from the pile, means for simultaneously oscillating said sucker in coöperative relation with said sucker-moving means, an air-exhausting means to produce a partial vacuum in the sucker, means for breaking said vacuum, means to move said separated roll into contact with the other roll to engage said detached end, means for operating said vacuum-breaking means when said rolls have engaged said sheet, and means for rotating said rolls in unison to draw the sheet from the pile.

46. In a sheet-feeder, the combination with a support for a pile of sheets, of a pair of rotatable pull-out rolls, means to move one of said rolls to make an opening therebetween, a pneumatic sucker for detaching one end of the outer sheet from the pile, means for moving said sucker toward and from the pile, means for oscillating said sucker in coöperative relation with said sucker-moving means, an air-exhausting means to produce a partial vacuum in the sucker, means for breaking said vacuum, means to move said separated roll into contact with the other roll to engage said detached end, means for operating said vacuum-breaking means when said rolls have engaged said sheet, means for rotating said rolls in unison to draw the sheet from the pile, and means for relieving the inherent weight of the pile upon said sheet during withdrawal.

47. In a sheet-feeder, the combination with a support for a pile of sheets, of a pair of rotatable pull-out rolls, means to move one of said rolls to make an opening therebetween, a pneumatic sucker for detaching one end of the outer sheet from the pile, means for moving said sucker toward and from the pile, means for oscillating said sucker in coöperative relation with said sucker-moving means, an air-exhausting means to produce a partial vacuum in the sucker, means for breaking said vacuum, means to move said separated roll into contact with the other roll to engage said detached end, means for operating said vacuum-breaking means when said rolls have engaged said sheet, means for rotating said rolls in unison to draw the sheet from the pile, and means for momentarily reliev-

ing the inherent weight of the pile upon said sheet during withdrawal.

48. In a sheet-feeder, the combination with a support for a pile of sheets, of a pair of rotatable pull-out rolls, means to move one of said rolls to make an opening therebetween, a pneumatic sucker for detaching one end of the outer sheet from the pile, means for moving said sucker toward and from the pile, means for simultaneously oscillating said sucker in coöperative relation with said sucker-moving means, an air-exhausting means to produce a partial vacuum in the sucker, means for breaking said vacuum, means to move said separated roll into contact with the other roll to engage said detached end, means for operating said vacuum-breaking means when said rolls have engaged said sheet, means for rotating said rolls in unison to draw the sheet from the pile, and means for momentarily relieving the inherent weight of the pile upon said sheet during withdrawal.

49. In a sheet-feeder, the combination with a support for a pile of sheets on edge, comprising a series of vertically-movable hold-back fingers engaging the upper margins of the pile, of a pair of flexible clips bearing against the side margins of the pile, a pneumatic sucker for detaching one end of the outer sheet from the pile, when said fingers are raised, a pair of rotatable pull-out rolls, means to lift the upper of said rolls to make an opening therebetween, means for reciprocating said sucker while oscillating same toward and from the pile, an air-exhausting means to produce a partial vacuum in the sucker, means for breaking said vacuum, means to lower said upper roll to engage said detached end, means for operating said vacuum-breaking means after said rolls have engaged said sheet, and means for rotating said rolls in unison to draw the sheet from the pile.

50. In a sheet-feeder, the combination with a support for a pile of sheets on edge, comprising a series of vertically movable hold-back fingers engaging the upper margins of the pile, of a pair of flexible clips bearing against the side margins of the pile, a pneumatic sucker for detaching one end of the outer sheet from the pile, when said fingers are raised, a pair of rotatable pull-out rolls, means to lift the upper of said rolls to make an opening therebetween, means for lifting and lowering said suckers while simultaneously oscillating same toward and from the pile, an air-exhausting means to produce a partial vacuum in the sucker, means for breaking said vacuum, means to lower said upper roll to engage said detached end, means for operating said vacuum-breaking means after said rolls have

engaged said sheet, and means for rotating said rolls in unison to draw the sheet from the pile.

51. In a sheet-feeder, the combination with a support for a pile of sheets on edge, comprising a series of vertically movable hold-back fingers engaging the upper margins of the pile, of a pair of flexible clips bearing against the side margins of the pile, a pneumatic sucker for detaching one end of the outer sheet from the pile, when said fingers are raised, a pair of rotatable pull-out rolls, means to lift the upper of said rolls to make an opening therebetween, means for reciprocating said sucker while oscillating same toward and from the pile, an air-exhausting means to produce a partial vacuum in the sucker, means for breaking said vacuum, means to lower said upper roll to engage said detached end, means for operating said vacuum-breaking means after said rolls have engaged said sheet, means for rotating said rolls in unison to draw the sheet from the pile, and means for relieving the inherent weight of the pile upon said sheet during withdrawal.

52. In a sheet-feeder, the combination with a support for a pile of sheets on edge, comprising a series of vertically movable hold-back fingers engaging the upper margins of the pile, of a pair of flexible clips bearing against the side margins of the pile, a pneumatic sucker for detaching one end of the outer sheet from the pile, when said fingers are raised, a pair of rotatable pull-out rolls, means to lift the upper of said rolls to make an opening therebetween, means for lifting and lowering said suckers while simultaneously oscillating same toward and from the pile, an air-exhausting means to produce a partial vacuum in the sucker, means for breaking said vacuum, means to lower said upper roll to engage said detached end, means for operating said vacuum-breaking means after said rolls have engaged said sheet, means for rotating said rolls in unison to draw the sheet from the pile, and means for relieving the pressure of the pile upon said sheet during withdrawal.

53. In a sheet-feeder, the combination with a support for a pile of sheets on edge, comprising a series of vertically movable hold-back fingers engaging the upper margins of the pile, of a pair of flexible clips bearing against the side margins of the pile, a pneumatic sucker for detaching one end of the outer sheet from the pile, when said fingers are raised, a pair of rotatable pull-out rolls, means to lift the upper of said rolls to make an opening therebetween, means for reciprocating said sucker while oscillating same toward and from the pile.

- an air-exhausting means to produce a partial vacuum in the sucker, means for breaking said vacuum, means to lower said upper roll to engage said detached end, means for operating said vacuum-breaking means after said rolls have engaged said sheet, means for rotating said rolls in unison to draw the sheet from the pile, and means for momentarily relieving the inherent weight of the pile upon said sheet during withdrawal. 65
54. In a sheet-feeder, the combination with a support for a pile of sheets on edge, comprising a series of vertically movable hold-back fingers engaging the upper margins of the pile, of a pair of flexible clips bearing against the side margins of the pile, a pneumatic sucker for detaching one end of the outer sheet from the pile, when said fingers are raised, a pair of rotatable pull-out rolls, means to lift the upper of said rolls to make an opening therebetween, means for lifting and lowering said suckers while simultaneously oscillating same toward and from the pile, an air-exhausting means to produce a partial vacuum in the sucker, means for breaking said vacuum, means to lower said upper roll to engage said detached end, means for operating said vacuum-breaking means after said rolls have engaged said sheet, means for rotating said rolls in unison to draw the sheet from the pile, and means for momentarily relieving the inherent weight of the pile upon said sheet during withdrawal. 70
55. In a sheet-feeder, the combination with a support for a pile of sheets on edge, of a pneumatic sucker for detaching one end of the outer sheet from the pile, rotatable means carried by the sucker, means for engaging said detached end and withdrawing the sheet from the pile, and a single mechanism, comprising a coacting rock-lever, rock-arm and link connection with the feeder, for raising and rotating said sucker toward, and for lowering and rotating said sucker away from, the pile to bend said detached end over said rotatable means within said sheet-engaging means. 75
56. In a sheet-feeder, the combination with a support for a pile of sheets on edge, of a plurality of pneumatic suckers for detaching one end of the outer sheet from the pile, rotatable means carried by the sucker, means for engaging said detached end and withdrawing the sheet from the pile, and means, comprising a rock-arm and link connection with the feeder, for raising and rotating said suckers toward, and for lowering and rotating said suckers away from, the pile to bend said detached end over said rotatable means within said sheet-engaging means. 80
57. In a sheet-feeder, the combination with a support for a pile of sheets on edge, of a pneumatic sucker for detaching one end of the outer sheet from the pile, rotatable means carried by the sucker, means for engaging said detached end and withdrawing the sheet from the pile, and a single mechanism, comprising a coacting rock-lever, rock-arm and link connection with the feeder, for raising and rotating said sucker toward, 85
58. In a sheet-feeder, the combination with a support for a pile of sheets on edge, of a plurality of pneumatic suckers for detaching one end of the outer sheet from the pile, rotatable means carried by the suckers, means for engaging said detached end and withdrawing the sheet from the pile, and means, comprising a rock-arm and link connection with the feeder, for raising and rotating said suckers toward, and for lowering and rotating said suckers away from, the pile, in unison, to bend said detached end over said rotatable means within said sheet-engaging means. 90
59. In a sheet-feeder, the combination with a support for a pile of sheets on edge, of a pneumatic sucker for detaching one end of the outer sheet from the pile, rotatable means carried by the sucker, means for engaging said detached end and withdrawing the sheet from the pile, and a single mechanism, comprising a coacting rock-lever, rock-arm and link connection with the feeder, for raising and rotating said sucker toward, and for lowering and rotating said sucker away from, the pile to bend said detached end over said rotatable means within said sheet-engaging means. 95
60. In a sheet-feeder, the combination with a support for a pile of sheets on edge, of a plurality of pneumatic suckers for detaching one end of the outer sheet from the pile, rotatable means carried by the suckers, means for engaging said detached end and withdrawing the sheet from the pile, and a single mechanism, comprising a coacting rock-lever, rock-arm and link connection with the feeder, for raising and rotating said suckers toward, and for lowering and rotating said suckers away from, the pile to bend said detached end over said rotatable means within said sheet-engaging means. 100
61. In a sheet-feeder, the combination with a support for a pile of sheets on edge, of a pneumatic sucker for detaching one end of the outer sheet from the pile, rotatable means carried by the sucker, means for engaging said detached end and withdrawing the sheet from the pile, and a single mechanism, comprising a coacting rock-lever, rock-arm and link connection with the feeder, for raising and rotating said sucker toward, 105
62. In a sheet-feeder, the combination with a support for a pile of sheets on edge, of a plurality of pneumatic suckers for detaching one end of the outer sheet from the pile, rotatable means carried by the suckers, means for engaging said detached end and withdrawing the sheet from the pile, and means, comprising a rock-arm and link connection with the feeder, for raising and rotating said suckers toward, and for lowering and rotating said suckers away from, the pile to bend said detached end over said rotatable means within said sheet-engaging means. 110
63. In a sheet-feeder, the combination with a support for a pile of sheets on edge, of a pneumatic sucker for detaching one end of the outer sheet from the pile, rotatable means carried by the sucker, means for engaging said detached end and withdrawing the sheet from the pile, and a single mechanism, comprising a coacting rock-lever, rock-arm and link connection with the feeder, for raising and rotating said sucker toward, 115
64. In a sheet-feeder, the combination with a support for a pile of sheets on edge, of a plurality of pneumatic suckers for detaching one end of the outer sheet from the pile, rotatable means carried by the suckers, means for engaging said detached end and withdrawing the sheet from the pile, and means, comprising a rock-arm and link connection with the feeder, for raising and rotating said suckers toward, 120
65. In a sheet-feeder, the combination with a support for a pile of sheets on edge, of a pneumatic sucker for detaching one end of the outer sheet from the pile, rotatable means carried by the sucker, means for engaging said detached end and withdrawing the sheet from the pile, and a single mechanism, comprising a coacting rock-lever, rock-arm and link connection with the feeder, for raising and rotating said sucker toward, 125

and for lowering and rotating said sucker away from, the pile, in unison, to bend said detached end over said rotatable means within said sheet-engaging means.

62. In a sheet-feeder, the combination with a support for a pile of sheets on edge, of a plurality of pneumatic suckers for detaching one end of the outer sheet from the pile, rotatable means carried by the suckers, means for engaging said detached end and withdrawing the sheet from the pile, and a single mechanism, comprising a coacting rock-lever, rock-arm and link connection with the feeder, for raising and rotating said suckers toward, and for lowering and rotating said suckers away from the pile, in unison, to bend said detached end over said rotatable means within said sheet-engaging means.

63. In a sheet-feeder, the combination with a support for a pile of sheets on edge, of a pneumatic sucker for detaching one end of the outer sheet from the pile, rotatable means carried by the sucker, means for engaging said detached end and withdrawing the sheet from the pile, and means, comprising a rock-arm and link connection with the feeder, for simultaneously raising and rotating said sucker toward, and for simultaneously lowering and rotating said sucker away from, the pile to bend said detached end over said rotatable means within said sheet-engaging means.

64. In a sheet-feeder, the combination with a support for a pile of sheets on edge, of a plurality of pneumatic suckers for detaching one end of the outer sheet from the pile, rotatable means carried by the suckers, means for engaging said detached end and withdrawing the sheet from the pile, and means, comprising a rock-arm and link connection with the feeder, for simultaneously raising and rotating said suckers toward, and for simultaneously lowering and rotating said suckers away from, the pile to bend said detached end over said rotatable means within said sheet-engaging means.

65. In a sheet-feeder, the combination with a support for a pile of sheets on edge, of a pneumatic sucker for detaching one end of the outer sheet from the pile, rotatable means carried by the sucker, means for engaging said detached end and withdrawing the sheet from the pile, and means, comprising a rock-arm and link connection with the feeder, for simultaneously raising and rotating said sucker toward and for simultaneously lowering and rotating said sucker away from, the pile, in unison, to bend said detached end over said rotatable means within said sheet-engaging means.

66. In a sheet-feeder, the combination with a support for a pile of sheets on edge, of a plurality of pneumatic suckers for de-

taching one end of the outer sheet from the pile, rotatable means carried by the suckers, means for engaging said detached end and withdrawing the sheet from the pile, and means, comprising a rock-arm and link connection with the feeder, for simultaneously raising and rotating said suckers toward, and for simultaneously lowering and rotating said suckers away from, the pile, in unison, to bend said detached end over said rotatable means within said sheet-engaging means.

67. In a sheet-feeder, the combination with a support for a pile of sheets on edge, comprising a series of vertically movable hold-back fingers engaging the upper margins of the pile, of means for detaching the outermost sheet from the pile, means, comprising a series of flexible clip members, for supporting the upper body of the pile, when said fingers are raised to permit the detaching means to withdraw said outermost sheet from the pile, and means for lowering said fingers when said sheet is detached from the pile.

68. In a sheet-feeder, the combination with an inclined support for a pile of sheets on edge, comprising a series of vertically movable hold-back fingers engaging the upper margins of the pile, of means for detaching the outermost sheet from the pile, means, comprising a series of flexible clip members, for supporting the upper body of the pile, when said fingers are raised to permit the detaching means to withdraw said outermost sheet from the pile, and means for lowering said fingers when said sheet is detached from the pile.

69. In a sheet-feeder, the combination with a support for a pile of sheets on edge, comprising a series of vertically movable hold-back fingers engaging the upper margins of the pile, of means for detaching the outermost sheet from the pile, and rotatable means carried by said detaching means for supporting the upper body of the pile, when said fingers are raised to permit the detaching means to withdraw said outermost sheet from the pile.

70. In a sheet-feeder, the combination with an inclined support for a pile of sheets on edge, comprising a series of vertically movable hold-back fingers engaging the upper margins of the pile, of means for detaching the outermost sheet from the pile, and rotatable means carried by said detaching means for supporting the upper body of the pile, when said fingers are raised to permit the detaching means to withdraw said outermost sheet from the pile.

71. In a sheet-feeder, the combination with a support for a pile of sheets on edge, of pneumatic sucker devices for detaching one end of the outer sheet from the pile,

and rotatable means carried by the sucker devices for supporting the upper body of the pile, while the sucker devices are withdrawing the outer sheet from the pile.

5 72. In a sheet-feeder, the combination with an inclined support for a pile of sheets on edge, of pneumatic sucker devices for detaching one end of the outer sheet from

the pile, and rotatable means carried by the sucker devices for supporting the upper 10 body of the pile, while the sucker devices are withdrawing the outer sheet from the pile.
